United States Patent

Des. 239,477
Patented Apr. 13, 1976

239,477

HAT COVER

Eloise Ellis, 320 SE. 89th St. 73149, and Anita F. Kilgore, 8500 S. Shartel 73139, both of Oklahoma City, Okla.

Filed Jan. 21, 1974, Ser. No. 435,240

Term of patent 14 years

Int. Cl. D2—03

U.S. Cl. D2—260

FIG. 1.

FIG. 2.

FIG. 6.

FIG. 1 is a side elevational view of a hat cover showing our new design;

FIG. 2 is a front elevational view thereof;

FIG. 3 is a rear elevational view;

FIG. 4 is a bottom plan view on a reduced scale;

FIG. 5 is a top plan view thereof; and

FIG. 6 is a front perspective view of the hat cover in a wearing position over a hat.

We claim:

The ornamental design for a hat cover, substantially as shown and described.
